UNITED STATES PATENT OFFICE.

WILLIAM KIRCHNER, OF SPARTA, WISCONSIN.

POWER HAMMER.

Application filed May 12, 1924. Serial No. 712,776.

This invention relates to a power hammer, one of the objects being to provide a hammer which can be adjusted angularly to strike blows in any direction desired, thus adopting the device particularly to machine shop work where it is desired to rivet, weld and hammer out metal located at different angles relative to the base of the hammer.

A further object is to provide a structure 10 of this character which is simple, durable and compact and can be operated readily.

With the foregoing and other objects in view which will appear as the description proceeds, the invention resides in the combination and arrangement of parts and in the details of construction hereinafter described and claimed, it being understood that changes in the precise embodiment of the invention hereinafter described and 20 claimed may be made within the scope of what is claimed without departing from the spirit of the invention.

In the accompanying drawings the preferred form of the invention has been 25 shown.

In said drawings

Figure 1 is a front elevation of the power hammer, one of the positions to which the same can be adjusted being indicated by 30 broken lines.

Fig. 2 is a view partly in side elevation and partly in section of the power hammer.

Fig. 3 is a top plan view.

Fig. 4 is a section on line 4—4, Fig. 2.

Referring to the figures by characters of reference 1 designates a base provided with a pedestal 2 and preferably with an anvil 3. A tubular shank 4 is mounted for rotation in the pedestal and extends from a 40 tiltable arm 5 adapted to be adjusted to any desired angle relative to the base about the axis of the shank 4. Any suitable means may be employed for holding the shank against rotation in the pedestal and in the 45 drawings a set screw 6 has been illustrated for this purpose. Obviously any other means may be employed if desired. Furthermore, and as shown in Figs. 2 and 4, suitable grease or oil cups 7 may be provided 50 on the pedestal for directing a lubricant into grooves 8 provided in the shank 4 and from which are extended openings 9. These openings are adapted to feed lubricants to a shaft 10 journaled in the shank 4 and 55 provided at one end with a pulley 11

adapted to be driven by a belt or any other means.

The arm 5 is provided, near its lower end, with guide cleats 12 between which is mounted a dove-tail 13 carried by a slideable 60 head 14. The lower end of this head has an extension 15 constituting a hammer. The guides 12 not only serve to hold the head 14 movably assembled with the arm 5 but also serve to hold the dove-tail 13 spaced 65 from the face of the arm 5. Thus there is room between the arm 5 and the dove-tail 13 for the movement of a wrist pin 16 extending from a crank or disk 17. This crank or disk is rotatably mounted with a 70 recess 18 in arm 5 and is secured to the shaft 10.

Spaced guide cleats 20 are provided on the arm 5 near the upper end thereof and are slidably engaged by a block 21 to which 75 is pivotally connected the upper end of a pitman 22. The lower end of this pitman engages the wrist pin 16.

A stud 23 is extended outwardly from the block 21 and is connected by oppositely 80 bowed spring arms 24 to oppositely extending arms 25 fixed relative to the top portion of the head 14.

It will be obvious from the foregoing that when the shaft 19 is rotated motion will be 85 transmitted therefrom through the wrist pin 16 and pitman 22 to the blocks 21 which will thus be caused to reciprocate upon the guides 20. This reciprocation motion will be transmitted through the spring arm 24 90 and the rigid arms 25 to the head 14. Thus the hammer 15 can be driven against the anvil 3 or an object thereon, the spring arms 24 permitting it to rebound. By loosening the clamping means 6 the arm 5 can be 95 adjusted angularly so that the hammer 15 can reciprocate along lines of any desired angles relative to base 1. Thus work located at the side of the power hammer can be struck a blow at any angle desired by placing it 100 sufficiently close to receive the impact from the hammer 15. It is merely essential that, after the arm 5 has been adjusted to the proper angle, it be securely held by the clamping means 6. A suitable motor can be 105 utilized for driving the shaft 19 and it has been found in practice that, by means of a device such as herein described, very rapid powerful blows can be struck. Thus the apparatus is especially useful in machine 110

shops for forging and for riveting and is also advantageous as a means for drawing out drills such as used in drilling oil wells.

What is claimed is:—

- 5 In a power hammer the combination with a supporting structure, an anvil fixed relative thereto, an arm mounted to swing relative to the structure, and a crank mounted for rotation relative to the supporting structure, said arm being mounted to swing about the axis of rotation of the crank, of a hammer head mounted for reciprocation on the

arm, the axis of rotation of the crank extending at all times substantially through the center of mass of the head when the head is in any position, a block mounted for reciprocation upon one end portion of the arm, means operated by the crank for reciprocating the block, and resilient driving connections between the block and the hammer head. 15

In testimony that I claim the foregoing as my own, I have hereto affixed my signature.

WILLIAM KIRCHNER.
